UNITED STATES PATENT OFFICE.

TONY MOLINARO, OF SILVER LAKE, NEW JERSEY.

ROTARY SHOE-CLEANER.

1,228,195.

Specification of Letters Patent. Patented Apr. 17, 1917.

Application filed October 5, 1915. Serial No. 54,214.

To all whom it may concern:

Be it known that I, TONY MOLINARO, a citizen of the United States, residing at Silver Lake, in the county of Essex and 5 State of New Jersey, have invented new and useful Improvements in Rotary Shoe-Cleaners, of which the following is a specification.

This invention contemplates the provision 10 of a shoe cleaning machine as a substitute for the well known form of door mat.

The invention aims to provide a device of the above mentioned character embodying among other features a rotary brush mounted 15 upon a casing for quickly removing mud or the like from the shoe, and depositing the same in a suitable receptacle within the casing for disposal when desired.

Another object of the invention resides in 20 the provision of a device of this character with a novel construction of means for rotating the brush, whereby the device can be conveniently manipulated for the purpose intended.

25 A still further object of the invention resides in the manner of mounting the rotary brush within the casing whereby the same can be quickly and easily removed therefrom when desired for any purpose whatsoever.

30 Other objects will appear as the nature of the invention is better understood from the following description wherein the specific construction, combination and arrangement of parts of one embodiment of the invention 35 is fully set forth and clearly defined in the appended claims.

In the drawing forming part of this specification like numerals of reference indicate similar parts in the several views and 40 wherein:

Figure 1 is a perspective view of the device constructed in accordance with my invention.

Fig. 2 is a longitudinal sectional view.

45 Fig. 3 is a transverse sectional view taken on line 3—3 of Fig. 2.

Fig. 4 is a similar view taken on line 4—4 of Fig. 2.

50 Fig. 5 is a similar view taken on line 5—5 of Fig. 2.

Fig. 6 is an enlarged vertical sectional view of the tubular casing showing the operating shaft therein,

55 Fig. 7 is an enlarged detail view of one of the hollow bearings.

Referring more particularly to the draw-

ings 5 indicates a casing which may be constructed from any suitable material preferably non-corrosive metal, and preferably of rectangular formation in cross section, 60 including a bottom 6, side walls 7 and end walls 8 and 9 respectively. The casing is divided by the partition 10 into separate compartments 11 and 12 respectively.

Adjustably mounted through suitable 65 openings in the end wall 8 and the partition 10 are hollow exteriorly threaded alined sleeves 13, which project but a short distance within the compartment 11, and which receive the opposite ends of the shaft 14 70 upon which the brush is fixed for rotation therewith. The sleeves 13 are held associated with the end wall 8 and the partition 10 by means of the nuts 15 adjustably mounted 75 upon their respective shafts and adapted to engage against the opposite faces of the end wall 8 and the partition as shown. The brush is substantially in the form of a spool including a main portion 16 and end portions 17, whereby the sides as well as the 80 bottom of the shoe are thoroughly cleaned when brought into engagement with the end portions 17 while the brush is being rotated in the manner to be hereinafter described. It is of course to be understood that the 85 bristles must be very stiff, and may consequently be constructed from any material suitable for the purpose for which the brush is intended. The shaft 14 is provided with a squared bore 18 opening at one end thereof, for the reception of the squared portion 19 of the stub shaft 20, which latter is extended through the sleeve 13 mounted in the partition 10 and fixed upon the outer end of the shaft 20 is a gear wheel 21 disposed with- 90 in the compartment 12.

Adjustably mounted through a suitable opening in the end wall 9 of the casing is a sleeve 22 which projects a short distance within the compartment 12, and held fixed 100 relatively to the end wall 9 by means of the nuts 23 adjustably mounted upon the sleeve and engaging against the opposite faces of the end wall as shown. The sleeve 22 is adapted to receive one end of a shaft 24 which latter has its opposite end journaled in a bearing in the partition 10 and fixed upon the shaft 24 for rotation therewith is an internal gear wheel 25 having a circumferential series of teeth 26 extending about the inner periphery 110 thereof and meshing with the gear 21 for rotating the brush upon rotation of the shaft

24. Fixed upon the shaft 24 is a beveled gear 27 coöperating with a similar gear 28 carried by the lower end of a vertically disposed operating shaft 29 by means of which 5 rotary motion is imparted to the shaft 24. The casing is closed by means of a cover 30 of a size to project a slight distance beyond the walls of the casing, and secured thereto in any suitable manner, preferably by means 10 of the fastening bolts 31. The cover is provided adjacent one end with a suitable opening in which is threaded the lower end of a tubular casing 32, the latter being closed at its lower end except for a restricted opening 15 through which the operating shaft 29 projects, the casing being further secured to the cover by means of the nut 33 as shown. The tubular casing rises from the cover an appreciable distance and is closed at its upper 20 end by means of an enlarged cap 34 having a reduced interiorly threaded portion 35 threaded upon the upper portion of the casing 32. The operating shaft projects above the upper end of the casing 32 and has fixed 25 thereon a beveled gear 36 which is positioned within the cap 34. The cap is provided with an enlarged opening 37 which is closed by means of a disk 38, and journaled in said disk is a shaft 39 having fixed on one end 30 thereof a beveled gear 40 meshing with the gear 36, while secured to the outer end of the shaft 39 is a crank handle 41, which when operated rotates the shaft 29, the latter in turn imparting a rotary motion to the 35 shaft 24 through the medium of the beveled gear connection as shown, the gear wheel 25 being fixed upon the shaft 24 for rotation therewith, and meshing with the gear 21 in turn operating to rotate the brush for the 40 purpose intended. It will be noted that the mechanism for rotating the brush is housed within the compartment 12 and thereby protected from inclement weather, while the partition 10 prevents dirt, mud or other 45 foreign matter from entering the compartment which would obviously interfere with the efficiency of the machine. Similarly the operating shaft 29 and its gear connections are also protected from weather by means 50 of the casing 32 and the cap 34, the casing 32 being effectively braced by means of the brace rods 42 terminally connected at one end with the cover, and having their opposite ends secured in any suitable manner to a clamp 43 embracing the casing at a suitable point in its length.

The cover 30 is provided with an elongated opening 44 through which the brush partly projects, and secured to the cover at 55 one side of the opening is a foot rest 45. In use the heel of the shoe is placed upon the rest 45 and the brush rotated by turning the crank 41 in the manner hereinabove described, and while the brush is being rotated the shoe is being moved back and forth and from one end of the brush to the other into engagement with the end portions 17 thereof, will be thoroughly cleaned and relieved of the mud or dirt clinging thereto. The mud and dirt passes through the space 70 at the opposite sides of the brush into the casing and is deposited in a suitable receptacle 46 slidably fitted within the casing through an opening in one of the side walls thereof, the receptacle being provided with a handle 75 47 for withdrawing the same from the casing when it is desired to dispose of the mud and dirt contained within the receptacle. It will be manifest that by properly adjusting the hollow sleeve 13 in the end wall 8 and 80 in the partition 10 the brush may be easily removed from the casing subsequent to the removal of the cover therefrom, for the purpose of repairing the brush, cleaning the same, or substituting a new brush for an old 85 worn out one. The machine in addition to being easily manipulated is very efficient in its purpose.

It is believed that from the foregoing description the nature and advantages of the invention will be thoroughly understood without requiring a more extended explanation and therefore the same has been omitted. However I desire to have it understood that I do not limit myself to the 90 precise construction and arrangement of parts herein shown and described, as the same is merely illustrative of one embodiment of the invention, and that various changes in the construction and arrangement of parts may be resorted to when desired as fall within the scope of the appended claims.

What is claimed is:—

1. In a device of the class described in 105 combination a casing having a central partition, a pair of alining sleeves threaded into one wall of said casing and the partition respectively, a counter shaft mounted in said partition at one end and in another 110 wall of said casing at its opposite end, the outer bearings of said last named counter shaft being removable, and an internal gear fixed upon said counter shaft, and a sleeve threaded into said partition in which one 115 end of said counter shaft is received, said internal gear engaging said last named sleeve so as to be limited against movement in one direction, a stub shaft having a shoulder engaging one of said first named sleeves, 120 a small gear fixed upon said stub shaft and engaging in said internal gear and held against displacement by the latter, a brush spool, and a shaft carried by said brush spool and having at one end a polysided bore, one end of said last named shaft being received in one of said first named sleeves, 125 said stub shaft having a polysided portion fitting in said bore and adapted to rotate said brush spool.

2. In a device of the class described, in combination a casing, a partition in said casing, a brush spool having a polysided bore at one end and at its opposite end journaled in one wall of said casing, a stub shaft journaled in said partition and having a polysided portion fitting in said polysided bore and supporting said spool for rotation, said stub shaft being detachable from engagement with said spool to permit

5 the opposite end of the spool shaft to be

removed from the casing, a gear wheel carried by said stub shaft, a drive shaft adapted to have longitudinal movement, and an internal gear fixed upon said drive shaft, detachable from said first named gear by the longitudinal movement of said shaft and adapted to mesh with the latter to rotate the stub shaft.

15 In testimony whereof I affix my signature. 20

TONY MOLINARO.
